Patented Nov. 21, 1972

225,140

HEADBOARD FOR A BEDSTEAD OR SIMILAR ARTICLE

Huey T. Keller, 1609 Davidson Road,
High Point, N.C. 27262

Filed Aug. 10, 1970, Ser. No. 24,384

Term of patent 14 years

Int. Cl. D6—01

U.S. Cl. D5—4

The single figure is a front elevational view of a headboard for a bedstead or similar article, showing my new design, the rear, not shown, being substantially flat and unornamented.

I claim:

The ornamental design for a headboard for a bedstead or similar article, as shown and described.
